UNITED STATES PATENT OFFICE.

ADOLPH L. NELSON, OF INDIANAPOLIS, INDIANA.

PISTON.

Application filed June 2, 1923. Serial No. 643,073.

REISSUED

To all whom it may concern:

Be it known that I, ADOLPH L. NELSON, a citizen of the United States, residing at Indianapolis, in the county of Marion and 5 State of Indiana, have invented certain new and useful Improvements in Pistons, of which the following is a specification.

My said invention relates to a piston for internal combustion engines and the like and 10 it is an object of the invention to separate the skirt from the head so that the skirt may be largely insulated from the action of the heat on the head. In some instances also the skirt may be made of different material 15 from the head, for example the head may be made of cast iron to minimize wear in the ring grooves while the skirt may be of a relatively light and soft alloy.

The main object of the invention is to provide 20 a piston in which the skirt shall be relatively free from contraction and expansion being when cold in a condition of strain which is relieved when the skirt warms up but due to such strain there is very little actual 25 increase in diameter during the warming process. The advantages of such a construction in preventing or decreasing the piston slap when the engine is cold and in insuring the maintenance of a film of oil between 30 the piston and the cylinder at all times will be obvious to those skilled in the art.

Subsidiary purposes are to provide efficient 35 means for holding together the separate head and skirt, to provide means insuring correct alinement of the head and the skirt, and to provide improved means for preventing access of oil to the cylinder above the piston. Other purposes will appear upon 40 consideration of the subjoined description.

Referring to the accompanying drawings which are made a part hereof and on which similar reference characters indicate similar parts,

Figure 1 is a central vertical section of one form of my invention,

Figure 2, a horizontal section of Figure 1 immediately above the upper strut,

Figure 3, an inverted plan of Figure 1, 50 Figure 4, a vertical central section of another form of my invention, on line 4-4 of Figure 5,

Figure 5, a section at right angles to Figure 4,

Figure 6, a detail of the upper strut in Figures 4 and 5, and

Figure 7, a detail of a modified strut.

In the drawings reference character 10 indicates the head of the piston which is secured to the skirt 11 by means of bolts 12 60 engaging threaded openings in bosses 13 on the head and fitting loosely in openings through bosses 13' on the skirt. These bolts also extend through openings in the hollow piston pin 14 which is mounted in bearings 65 on the extensions 13 and is held in fixed position by the bolts.

The skirt has an annular rim at 15 extending upwardly to surround the lower portion of the head and a strut 16, preferably made 70 of a steel stamping, is located between the head and the adjacent part of the skirt, said strut fitting closely within the rim 15 except at the parts nearest to the bolts 12 where the strut is relieved to a slight extent as at 17 to allow for cases where the cylinders go out of round. It will be seen 75 that the strut acts as a rigid member to prevent contraction of the skirt in a direction transversely of the piston pin whereas a 80 slight contraction is permitted longitudinally of the piston pin by the relief at 17, 17. The strut 16 has a central aperture adapted to be engaged by a depending hollow boss 85 18 on the head of the piston. This boss fits closely within the opening and is of assistance in locating the head in alinement with the skirt. The strut is also provided at each side of a line passing through bolts 12 with 90 groups of openings 18' arranged in semi-circles.

Beneath the piston pin is a second strut 19 apertured at diametrically opposed points to accommodate the bolts 12 and made in the shape of a ring having an elliptical opening with its major axis transverse to the piston pin. This strut serves to limit the contraction of the lower part of the skirt in the same manner as strut 16 limits the contraction of the upper part and is relieved 95 at 19' in similar manner to strut 16. The piston pin is flattened near its ends for secure engagement by the lower strut and washers 20 are placed between the heads of the bolts and the lower strut, these washers each having 100 an arcuate surface at one side as indicated at 21 to bear against the inner surface of the skirt.

The skirt is slotted at intervals from above and below as shown at 22 and 23, these slits serving a double purpose in that the upper slits provide a means for the excess

oil to escape from the lowermost ring groove through the slits to the interior of the piston, while both the upper and the lower slits act to take care of the expansion 5 of the piston. As the temperture of the piston rises the tongues between adjacent grooves spread laterally by a sort of side-wise crawling action of their material to gradually fill the space normally occupied 10 by the slits but because of the limitation imposed on contraction by the upper and lower struts there will be little or no radial expansion while the contraction upon cooling will proceed in the reverse fashion by 15 the gradual narrowing of the tongues but unaffected by any considerable radial movement in the skirt. It should be noted also that the separation of the skirt from the head tends to insulate the skirt from the 20 high temperature of the head, which effect is augmented by the material of the upper strut which should be selected partly for its relative impermeability to heat.

In the form of the invention shown in 25 the figures heretofore described the upper strut has a series of holes at each side of a line passing through the bolts and a relief at each side at 17, the strut being otherwise in the shape of a disk. In the modification 30 of Figures 4 to 6 I have shown the upper strut 24 as having its outer periphery in the form of a complete circle with openings at both sides of a diameter passing through the bolts 25. This leaves a diametrical 35 bridge at 26 for bracing the strut. A bridge 26' at right angles to bridge 26, as shown in Figure 7, and this will be found preferable in some cases, the whole making a cruciform bridge structure combining the parts 40 26 and 26' to provide increased rigidity. The rigid brace formed by the bridge and the parts adjacent thereto is interrupted only by the bolt holes 27 which accommodate the bolts 25 with a slight clearance. 45 It will be seen that the upper strut thus provides a structure rigid in a direction parallel to the piston pin 14 but adapted to yield slightly in a direction transverse thereto. For limiting the expansion and 50 contraction of the upper end of the skirt the strut has an annular groove on its underside adapted to engage an annular flange at 28 on the skirt, the tongue 29 produced in forming the groove on the strut engaging 55 a groove in the skirt between the tongue 28 and the outer periphery of the skirt. This is the only one expedient for producing a secure engagement of the skirt and the strut and I may use other methods such as 60 will be obvious to those skilled in the art.

The head 10' is secured to the skirt 11' by the bolts 25' having heads 30 flush with the upper surface of the piston head and having knurled portions 31 with a press fit in the head.

The skirt is cut away at both sides beneath the piston bearing as shown at 33 and has slots 34 extending from the upper end to a point below the lower part of the piston pin, or otherwise expressed to a point below 70 the mid-length of the skirt. These slots and cut away portions provide space for the sidewise extension of the tongues formed thereby as above described and permit the skirt to be held against radial extension or 75 contraction by means of the upper strut 24 and a lower strut 19', the latter consisting of a substantially elliptical ring having an elliptical opening. The ends of the ring fit between raised parts 35 on the downwardly extending tongues of the skirt and the strut may be fastened to the parts 35 either permanently or otherwise as desired.

The bolts 25 fit in the holes in the skirt extensions 36 with a considerable clearance 85 and passages 37 lead to such holes from the exterior of the piston at the upper end of the skirt, for the purpose of leading excess oil to the interior of the piston.

Various modifications of my device and 90 the parts thereof will be obvious to those skilled in the art and therefore I do not limit myself to what is shown in the drawings and described in the specification but only as indicated in the appended claims. 95

Having thus fully described my said invention, what I claim as new and desire to secure by Letters Patent, is:

1. A piston having a head, a skirt separable therefrom, and a strut between the 100 head and the skirt said strut having means to engage the upper margin of the skirt for limiting the expansion and contraction thereof, substantially as set forth.

2. A piston having a head, a skirt separable therefrom and longitudinally slitted at its upper end, and a strut closely engaging the inner surface of the skirt at its upper margin to prevent contraction thereof, substantially 105 as set forth.

3. A piston having a head, a skirt separable therefrom and longitudinally slitted at its upper end, a strut closely engaging an inner surface of the skirt at its upper end to prevent contraction thereof said strut being in the form of a ring with a bridge 110 extending across the same in line with the piston pin, substantially as set forth.

4. A piston having a head, a skirt separable therefrom and longitudinally slitted at its upper end, a strut closely engaging the inner surface of the skirt at its upper end to prevent contraction thereof said strut being in the form of a ring with a bridge extending across the same, substantially as set 115 forth.

5. A piston having a head, a piston pin, a separable skirt having inner extensions forming bearings for the piston pin, bolts connecting the head and the piston pin to 120

the skirt said extensions having openings fitting loosely about the bolts and one or more oil passages leading to said openings from the upper end of the skirt, substantially as set forth.

6. A piston having a head, a skirt separable therefrom, an upwardly extending rim on the skirt, a strut fitting closely within the rim and separating the head and the skirt and a boss on the skirt fitting within an opening of the strut to aline the head and the skirt, substantially as set forth.

7. A piston having a head, a skirt separable therefrom having opposed inward extensions, an upwardly extending rim on the skirt, a piston pin, bolts extending upwardly through the piston pin and said extensions on the skirt and engaging threaded openings in the head, and a strut between the head and the skirt fitting closely within the said rim and relieved at opposite sides adjacent said bolts, substantially as set forth.

8. A piston having a head, a skirt separable therefrom having diametrically opposite inward extensions, bolts passing upward through the piston pin and said extensions into the head for securing the parts together said skirt having slits extending respectively from the upper and lower edges past the piston pin, and upper and lower struts to limit the contraction of the skirt, substantially as set forth.

9. A piston having a head a skirt separable therefrom having diametrically opposite inward extensions, a piston pin, bolts passing upward through the piston pin and said extensions into the head for securing the parts together said skirt having slits extending respectively from the upper and lower edges past the piston pin, and upper and lower struts bearing against the interior surface of the skirt to limit its contraction said lower strut being in the form of a ring resting against flattened end faces on the under side of the piston pin, substantially as set forth.

10. A piston having a head, a separable skirt having slits extending from its upper and lower edges past the midlength of the skirt, a strut at its upper end and a strut below such midlength fitting closely against the inner periphery of the skirt to prevent radial contraction thereof, substantially as set forth.

11. A piston having a head, a separable skirt, a strut separating the head and the skirt, bolts in a plane passing through the piston pin connecting the head and the skirt said strut being rigid in a direction transverse to the piston pin and being relieved at the sides nearest the piston pin, substantially as set forth.

12. A piston having a head, a skirt separable therefrom and longitudinally slotted at its upper end, a strut closely engaging the

inner surface of the skirt at its upper end to prevent contraction thereof said strut being in the form of a ring with a bridge extending across the same in line with the piston pin, substantially as set forth.

13. A piston having a head, a skirt separable therefrom and longitudinally slotted at its upper end, a strut closely engaging the inner surface of the skirt at its upper end to prevent contraction thereof said strut being in the form of a ring with bracing means in the form of a cruciform bridge, substantially as set forth.

14. A piston having a head, a skirt separable therefrom and longitudinally slotted at its upper end, a strut closely engaging the inner surface of the skirt at its upper end to prevent contraction thereof said strut being in the form of a ring with a cruciform bridge having one member extending across the ring in line with the piston pin and another at right angles thereto, substantially as set forth.

15. A piston having a head, a skirt separable therefrom having diametrically opposite inward extensions, bolts passing upward through the piston pin and said extensions into the head for securing the parts together said skirt having slits extending respectively from the upper and lower edges past the piston pin, and upper and lower struts to limit the contraction of the skirt, each of said struts being relieved at opposite sides adjacent to said bolts, substantially as set forth.

16. In a piston, a unitary head, a skirt, a unitary piston pin flattened at its lower side, bolts extending through the pin into the head, and means on said bolts engaging the flat side of the pin to secure it in place, substantially as set forth.

17. In a piston, a head, a skirt, a piston pin flattened at its lower side, bolts extending through the pin into the head, a flat-sided annular strut engaging the flat under side of the pin and the inside of the skirt, and means on the bolts engaging the strut to hold it in place, substantially as set forth.

18. In a piston, a head, a separate skirt having bosses at opposite sides with transverse apertures through the skirt, a piston pin in said apertures said skirt being cut away from said apertures to its lower rim to provide piston pin bearings open at the lower side, and bolts extending through the pin and the head to hold the parts together, substantially as set forth.

19. In a piston, a hollow head having bosses at opposite sides, a separate skirt having bosses in line with those on the head and having transverse apertures at their lower ends, a piston pin, and bolts passing through the pin and said bosses to fix the pin in place, substantially as set forth.

20. In a piston, a unitary head, a unitary

piston pin flattened at its lower side, an independent skirt having bosses arranged between the piston pins and the head, and bolts extending through the piston pins into
5 threaded engagement with the heads said bolts having heads engaging the flattened lower side of the piston pin, substantially as set forth.

In witness whereof, I have hereunto set my hand at Indianapolis, Indiana, this 28th 10 day of May, A. D. nineteen hundred and twenty-three.

ADOLPH L. NELSON.

Witnesses:

E. W. BRADFORD,
M. L. SHULER.
